[57] CLAIM

The ornamental design for a play structure, as shown and described.

DESCRIPTION

FIG. 1 is a perspective view of a play structure embodying the new design in a first configuration.

FIG. 2 is a perspective view of the play structure shown in FIG. 1 in a second configuration.

FIG. 3 is a right side view of the play structure shown in FIGS. 1-2, the left side view being a mirror image of FIG. 3.

FIG. 4 is a front view of the play structure shown in FIGS. 1-2 in the second configuration.

FIG. 5 is a back view of the play structure shown in FIGS. 1-2.

FIG. 6 is a top view of the play structure shown in FIGS. 1-2 in the second configuration; and,

FIG. 7 is a bottom view of the play structure shown in FIGS. 1-2.

Dashed lines in the drawings indicate environmental information that forms no part of the ornamental design of the play structure.
